UNITED STATES PATENT OFFICE.

CHARLES H. CORNELL, OF VALENTINE, NEBRASKA.

RAIL-FASTENER.

1,244,590.

Specification of Letters Patent. Patented Oct. 30, 1917.

Application filed March 23, 1917. Serial No. 156,805.

To all whom it may concern:

Be it known that I, CHARLES H. CORNELL, a citizen of the United States, residing at Valentine, in the county of Cherry and State of Nebraska, have invented certain new and useful Improvements in Rail-Fasteners, of which the following is a specification.

This invention relates to means for fastening rails to the ties and is intended to take the place of the usual spikes.

The objects of the present invention are to provide an improved form of rail fastener, which will be simple in construction and durable and efficient in operation; to provide a rail fastener which may be readily adjusted to tighten the rail; to provide a rail fastener having a bolt and a separately formed cam member, with means for locking these parts together; and to provide such an improved form of device as will appear more fully from the following description.

In the accompanying drawings illustrating this invention:

Figure 1 is a cross sectional view of a rail and tie showing my improved fastener in position;

Fig. 2 is a sectional view taken at right angles to Fig. 1;

Fig. 3 is a plan view of the fastener;

Fig. 4 is a perspective view of the bolt;

Fig. 5 is a side view showing a modified form of construction; and

Fig. 6 is a plan view of the cam member shown in Fig. 5.

As illustrated in these drawings, 7 represents an ordinary rail which rests on a tie 8. The bolt 9 passes down through a hole 40 10 in the tie, and its lower end is provided with a lateral lug or catch 11. The catch passes through a hole 12, which is similar 45 to a keyhole, in a plate 13 which rests against the bottom of the tie 8.

In accordance with my invention, the rail is tightened or pressed against the tie by 50 means of a cam-like member which coacts with the bolt 9. While these parts might in some cases be formed integrally, in the present instance I form them separately for convenience in manufacturing, and also for the purpose of enabling certain adjustments to be made. The bolt 9 is provided with a squared or angular head 14 for receiving a 55 wrench, and with a flange 15 having a transverse downwardly extending tongue or key

16. The cam member 17 is provided with a groove 18 for receiving the tongue 16, so that when this member is placed in position on the bolt 9, as shown in Figs. 1 and 2, it 60 will be turned by the tongue 16. The locking member 17 has its lower surface made in the form of a substantially helicoidal cam or screw 19, which engages with the flange of the rail 7. This fastening or cam 65 member 17 extends outwardly beyond the flange 15 and has a number of grooves or notches 20 in its outer periphery for receiving a nail 21, which is used to lock the device after it has been adjusted. 70

When the fastener is to be applied, the cam member 17 is placed in position on the bolt 9 and the bolt is then inserted with the lug or catch 11 through the hole 12. At this time the thin portion of the cam is in engagement with the rail flange. Then the bolt is turned by means of any ordinary wrench, which engages with the head 14. As the bolt is turned, the cam presses down 80 on the rail flange until the parts are pressed tightly together. The nail 21 is then driven into position and holds the fastener against rotation. If the rail becomes loosened, the tightener may be turned to adjust the same 85 for such wear or looseness. The bolts may be made of different lengths and the washers or cam members may be made of different thicknesses so as to permit the fastener being applied for different rails or ties of varying thickness. It will be seen 90 that by means of this arrangement the bolt is of simple construction and may be readily forged; and the separately formed cam member may also be readily formed, and when these members are assembled they will 95 turn together so that the fastener may be adjusted by means of any ordinary track wrench.

In the modified form of construction, shown in Figs. 5 and 6, the bolt 22 has a 100 flange 23, with a transverse shoulder 24. The separately formed cam washer 25 is provided with a shoulder 26, which coacts with the shoulder 24 so that the washer will be turned with the bolt. 105

It will be seen that various modifications may be made in the details of construction of my improved fastener, and therefore I do not wish to limit myself to the exact construction herein shown and described 110 further than is specified in the following claims, in which I claim:

1. In a rail fastener, the combination of a bolt having a projecting flange, a separately formed cam member, and means for fastening the cam member to the flange.
- 5 2. In a device of the character set forth, the combination of a bolt having an angular head and having an outwardly extending flange adjacent to the head, a tongue projecting from said flange, a cam member fitting over said bolt and having a groove for receiving said tongue.
- 10 3. In a rail fastener, the combination of a bolt having an outwardly extending head portion, a separately formed cam member fitting over said bolt, and interlocking means for causing the cam member to turn with the head portion.
- 15 4. The combination with a fastening bolt

for a rail, having an outwardly projecting flange adjacent to the head, of a removable locking member having its lower surface made in the form of a helicoidal cam and means for fastening the locking member to the flange whereby it will turn with the bolt.

25 5. The combination of a tie, a plate on the lower surface of the tie, a bolt passing through said tie and having an outwardly extending projection at its upper end, means for locking the lower end of the bolt to the 30 plate, a rail, a cam washer mounted on said bolt, having its cam surface engaging with the rail flange, and interlocking means between the washer and projection whereby the washer will be turned with the bolt.

35 CHARLES H. CORNELL.
